[57] CLAIM

The ornamental design for a portable ceramic heater, as shown and described.

DESCRIPTION

FIG. 1 is a perspective view of a portable ceramic heater showing my new design;

FIG. 2 is another perspective view of the portable ceramic heater of FIG. 1;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof;

FIG. 9 is an enlarged view of the control switches and knobs portion of FIG. 3, shown separately for clarity of illustration; and

FIG. 10 is an enlarged front elevational view being partially broken away to show the elements under the front screen.

Stripping in the above described drawings indicates a textured surface, it is not intended to represent adhesive, foam, or any similar material.

The rectangular middle portion in FIG. 8, represents a filter.
